LAUNDRY MACHINE

Nicholas L. Etten, Waterloo, Iowa, assignor to
Walter K. Voss, Davenport, Iowa

Application January 13, 1934, Serial No. 706,466

5 Claims. (Cl. 68—32)

The invention relates to laundry machines and more particularly to power driven wringers and mechanisms associated therewith for insuring the safety of the operator.

5 An object of the invention is to provide, in a laundry machine provided with a power driven wringer, a new and improved means for stopping the operation of the wringer when an overload is placed on the driving means for the machine.

10 Another object of the invention is to provide, in a machine of this nature, new and improved means for releasing the operative pressure normally applied to the rolls of the wringer when an overload is encountered by the mechanism.

15 Another object of the invention resides in the provision, in a laundry machine having a power driven wringer, mechanism which includes a safety release device for relieving the operating pressure under which the wringer rolls normally operate, of means responsive to an overload on the driving means for actuating said safety release mechanism to relieve said operating pressure between the rolls.

20 A further object is to provide a new and improved wringer mechanism having power driven rolls normally maintained under an operative pressure, and means operable when an excess load is placed on said rolls to release said pressure and to discontinue the driven operation of the rolls.

25 Other objects and advantages will become apparent in the following description and from the accompanying drawings, in which:

30 Figure 1 is a side elevation of a laundry machine embodying the features of the invention.

35 Fig. 1^a is a fragmentary view in elevation of the wringer assembly illustrating part of the holding mechanism for maintaining the wringer rolls under pressure.

40 Fig. 2 is a vertical longitudinal section on a transverse scale through the wringer assembly.

45 Fig. 3 is a wiring diagram of the control circuits of the laundry machine.

50 While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

55 The laundry machine which has been shown

in the drawings, merely for the purpose of illustrating the invention, is similar in many respects to that illustrated and described in copending application of Walter K. Voss and Nicholas L. Etten, Serial No. 604,178, filed April 9, 1932, and reference thereto may be had to obtain a particular description of the structure and operation of the features common to both machines. For the purpose of facilitating understanding of the present invention, however, a brief description of the essential features of construction thereof is given.

With reference to Fig. 1, a conventional laundry machine tub and supporting frame therefor is designated by the numeral 10. Within the tub 15 is an agitator actuating shaft 11 which is driven by an electric motor 12 through suitable driving connections located in the casing 13. Other connections in said casing actuate a vertical drive shaft 14 (Fig. 2) within a sleeve 15. The shaft 14 is the wringer drive shaft and rotates one roll 20 of a pair of cooperating wringer rolls 16, 17. Operative control of the rolls for movement in either direction from a neutral position is effected by a suitable gear and clutch mechanism 18 which 25 is manipulable through a clutch shaft 19.

The wringer structure is rigidly supported from a gear casing 20, within which the clutch mechanism is mounted, and embodies generally a U-shaped frame having hollow or channeled side 30 stiles 21. In this instance the lower wringer roll 16 is driven and it is rotatably supported by a shaft 22 which rests at each end upon bearings 23 located in the channel of the side stiles. The upper roll 17 runs in contact with the lower roll 35 and is driven thereby. This roll is supported upon a shaft 24 and the ends of the shaft within the side stiles have half-bearings 25 resting thereon. A separate relatively movable channeled head 26 is arranged to fit telescopically over the upper 40 ends of the side stiles. A leaf spring 27 is supported within the head by a tensioning device 28 in such manner that the ends of the spring may transmit a force to the half-bearings 25 and thence to the upper wringer roll 17 for maintaining the wringer rolls under an operative 45 pressure.

The head and wringer frame are provided with interlatching or interlocking means which is instantly detachable or releasable to relieve the rolls 50 from the operative pressure normally imposed thereon. Such an arrangement is conventionally known as a safety release mechanism, and in this embodiment, comprises the following structure. The head 26 at each end has U-shaped members 55

29 and 30 pivotally supported thereon through their ends for downward extension into the side stiles of the frame. The U-shaped members are in the nature of stirrups which embrace the bearings and shafts in the respective side stiles and the base of each stirrup is located near the bottom of the frame. One of the stirrups, in this instance the one located at the right-hand side of the frame as seen in Fig. 2, and designated 30, 10 has aligned and transversely facing recesses 31, formed intermediate the upper and lower ends of the arms, for engagement with a pin 32 on the frame, the parts being so positioned and arranged that engagement between the recesses 31 and pin 15 32 is effected by a lateral and downward movement of the head in the act of assembling the corresponding end of the head telescopically over its associated side stile.

The stirrup 29 at the other end of the wringer 20 is arranged for engagement by an impositive latch mechanism which in and of itself cannot exert a force for holding the head in operative position on the frame. To this end the frame carries a pivoted latch 33 arranged to be hooked 25 over the base 34 of the stirrup 29. An arm 35 is secured rigidly to the latch and extends upwardly along and exteriorly of the side stile. The relationship of these parts preferably is such that the latch 33 can be maintained in operative holding 30 engagement with the base of the stirrup 29 only when a holding force is exerted on the lever arm 35. If such a force is not present or is suddenly released, the tension of the leaf spring 27 which is exerted, in effect, between the head and frame 35 is sufficient to swing the latch 33 about its pivot, thus releasing the associated end of the head for upward movement. This movement in turn disengages the interlatch between the interlatching parts 31, 32 at the other end of the frame. 40 The force for holding the arm 35 in operative position is, in the present device, electromagnetically applied. Thus, near its upper end the arm 35 carries an outwardly and horizontally extending arm 36 which is engaged and held by the 45 armature 37^a of an electromagnet 37 when the armature is attracted toward said electromagnet. Whenever the electromagnet is deenergized, the arms 35, 36 are released, the latch 33 swings out of engagement with the stirrup base 34 and the 50 operative pressure between the wringer rolls is relieved.

Figure 3 illustrates a wiring diagram of the electrical circuits by which energization of the electromagnet is controlled. Connection of the 55 circuit with a suitable source of current is obtained through a plug 38 from one terminal of which a lead 39 connects with one point 40 of a three point connection block 41. A lead 42 from the point 40 extends to one contact 43 of a master 60 switch. A lead 44 from the other terminal of the plug 38 is connected with a second point 45 of the connection block 41 from which point a lead 46 extends to one side of the motor 12. A lead 47 from the other side of the motor 12 is 65 connected with the third point 48 of the connection block and from this point a lead 49 extends to one contact point 50 of a double-pole manually 70 controllable switch 51. A movable contact 52 which cooperates with the contact point 50 is connected through a lead 53 with the other contact 54 of the master switch. A circuit across the contacts 43, 54 of the master switch is closed by a conducting bar 55 which is mounted on the armature 56 of the electromagnet 37 and is held 75 against said contacts when the electromagnet is

energized. The circuit across the master switch contacts 43 and 54 is manually closed as by the act of the operator in moving the arm 35 to effect an engagement between the latch 33 and the base of the stirrup 29 when the wringer is being conditioned for operation. 5

The circuit thus far described is the motor energizing circuit and may be traced from the plug 38 through lead 39, point 40, lead 42, contact 43, conducting bar 55, contact 54, lead 53, switch 10 parts 52 and 50, lead 49, terminal 48, lead 47, motor 12, lead 46, terminal 45 and lead 44 to the plug.

The energizing circuit for the electromagnet 37 is as follows: From the terminal point 45 a 15 lead 58 is connected with one terminal 59 of a switch 60. The circuit through the switch 60 to the other terminal 61 is closed by a conductor bar 62 which is supported upon the movable core 63 of a solenoid, the purpose of which will be herein-after set forth. From the terminal 61 a lead 64 extends to one end of a winding 65 for the electromagnet 37 and a lead 66 from the other end of the winding 65 is connected with one terminal 67 of a normally closed switch 68. The other terminal 69 20 of said switch is connected by a lead 70 with a contact point 71 in the double-pole manually controlled switch 51. A cooperative movable contact 72 is connected by a lead 73 with the lead 53 25 which has direct connection through the master switch with the source of current. Hence, when the master switch is closed by movement of the conducting bar 55 into engagement with contacts 43 and 54, the electromagnet 37 will be energized 30 to hold the parts in circuit closing position as long as the other switches in the circuit are closed. Interruption of the circuit through any switch de-energizes the electromagnet 37, releases the armature 56 and breaks the circuit through the master switch thereby stopping the driven operation of 40 the motor 12. Release of the armature, as has been pointed out releases the wringer rolls from the operating pressure imposed thereon.

The normally closed switch 68 is arranged to be 45 opened by movement of an impact bar assembly 74 which is located on both sides of the wringer frame in a position which is convenient and accessible to the operator whereby in an emergency the switch 68 may be instantly opened to de-energize the electromagnet with the operative results previously described. Lead 68^a is connected across leads 53 and 70 to provide a shunt circuit 50 around the manually operable switch 51 so that this switch may be opened and closed to interrupt 55 the motor circuit without opening the energizing circuit for the electromagnet 37. Interposed in this shunt lead 68^a is a switch 68^b which is associated with the clutch actuating shaft so as to be closed only when the clutch mechanism 18 is in 60 neutral position. Hence the manually operable switch 51 can be actuated to break the motor circuit without opening the electromagnet circuit only when the clutch mechanism is in neutral.

The present device embodies means for interrupting the circuit of the motor to stop the driven movement of the rolls immediately upon the imposition of an excess load or overload upon the motor. Moreover, this means is adapted, upon the imposition of an overload, to release the mechanism by which the rolls are normally maintained under pressure. Thus, if the overload is imposed on the wringer rolls, as when an unusually large mass of clothes is fed therebetween or when some part of the operator's body becomes caught be- 70 75

tween the rolls, damage to the rolls or further injury to the operator is prevented.

A preferred form of such a means embodies the following arrangement of parts. The movable 5 solenoid core 63 is normally urged by spring means 75 into a position wherein the circuit through the switch 60 is closed. Associated with the solenoid core 63 is an energizing winding 16 which is interposed in series in the lead 42. The winding 16 is 10 thus included in the motor energizing circuit and the pull of the winding is so predetermined that under normal operating conditions its force is insufficient to overcome the opposing force of the spring 75. The circuit through the switch 60, 15 therefore, remains closed. However, when an overload is imposed on the motor 12 the additional current flow resulting therefrom increases the pull of the winding 16 until its force overcomes the tension of the spring 75 whereupon the core 63 moves to carry the conductor bar 62 away from the terminals 59, 61 to break the circuit through the switch 60. Since the switch 60 is connected 20 in the energizing circuit for the winding 65 of the electromagnet 37, opening of the switch deenergizes the electromagnet, instantly interrupts the motor driving circuit and at the same time releases the means by which the rolls are maintained under operative pressure.

If desired, a lamp 17 may be connected in shunt 30 across the leads 58 and 42 by leads 78 and 79 to provide a means for denoting a connection of the circuit with a source of current.

From the foregoing, it will be apparent that a 35 new and improved laundry machine has been provided wherein an overload imposed on the driving motor effects an interruption of the motor circuit to stop further operation of the motor and also to release the means by which the wringer 40 rolls are normally maintained under an operative pressure. The present invention results in an increased factor of safety to the operator and is a means for preventing injury or damage to the machine.

I claim as my invention:

45 1. In a laundry machine, the combination of a wringer mechanism including rolls, means for maintaining said rolls under an operating pressure, and means for releasing the rolls from said pressure, means for driving said rolls, and means

responsive to the imposition of any load on the driving means in excess of the load which the driving means is normally expected to encounter to discontinue operation of the roll driving means and to actuate the means for releasing the rolls 5 from said pressure.

2. In a laundry machine, the combination of wringer rolls, means for driving said rolls, means for applying pressure to said rolls including an electrically controlled device operable to release 10 said rolls from such pressure, a circuit including the roll driving means and said device, and means in said circuit responsive to an overload on the driving means for breaking the circuit to stop the roll driving means and to operate said device to 15 effect a release of pressure.

3. In a laundry machine, the combination of wringer rolls, means for driving said rolls, means for applying pressure to said rolls including an 20 electromagnet operable to release said rolls from such pressure, a circuit including the roll driving means and said electromagnet, and means in said circuit responsive to an overload for breaking the circuit to stop the roll driving means and to 25 operate said electromagnet to effect a release of pressure.

4. In a laundry machine, the combination of wringer rolls, means for applying an operating 30 pressure to said rolls including electromagnetic means operable to release such pressure, means for driving said rolls, and means responsive to an overload for operating said electromagnetic means to release said pressure when an overload is placed on the mechanism.

5. In a laundry machine, the combination of wringer rolls, means for driving said rolls including an energizing circuit, releasable means for maintaining said wringer rolls under an operating pressure including an electromagnetic device 40 for holding said releasable means against release, an energizing circuit for said electromagnetic device including a circuit breaker which is also common to said circuit for the driving means, a switch in the circuit for said electromagnetic device, and means responsive to an overload current in the circuit for the driving means for opening 45 said switch.

NICHOLAS L. ETTER.
